LOUIS J. WILDE AND BEE K. GILLESPIE, OF LOS ANGELES, CALIFORNIA.

APPARATUS FOR CLEANING AND POLISHING AUTOMOBILES.

Application filed March 26, 1925. Serial No. 18,550.

Our invention relates to and has for its purpose the provision of an apparatus by which the performance of the several operations necessary in the cleaning and polishing of automobiles both interiorly and exteriorly are greatly facilitated and in such manner that any number of automobiles can be cleaned and polished successively and in rapid order.

It is also the purpose of our invention to provide an apparatus of the above described character which embodies comparatively simple and inexpensive means for bodily and successively conveying a number of automobiles through a predetermined path from a given point and in such manner as to successively return the vehicle to the given point, each vehicle being moved slowly through the predetermined path so as to give the operators ample opportunity to perform the several operations of the cleaning and polishing of the car whereby a vehicle discharged onto the conveying means at a given point will be returned to such a point completely cleaned and polished.

We will describe only one form of apparatus for cleaning and polishing automobiles embodying our invention and will then point out the novel features thereof in claims.

In the accompanying drawings:

Figure 1 is a view showing in horizontal section one form of apparatus embodying our invention.

Figure 2 is a vertical sectional view taken on the line 2—2 of Figure 1.

Figure 3 is an enlarged fragmentary vertical sectional view taken on the line 3—3 of Figure 1.

Figure 4 is a fragmentary sectional view taken on the line 4—4 of Figure 1.

Referring specifically to the drawings in which similar reference characters refer to similar parts in each of the views, our invention in its present embodiment comprises a circular inclosure or building including a conical shaped roof 15 supported on an outer circular wall 16 and an inner circular wall 17 spaced from the outer wall so as to accommodate therebetween a circular pit 19 formed in the ground and over which the inclosure is adapted to be built. Extending inwardly from the inner walls 17 are radial walls 20 which co-operate with connecting walls 21 to form compartments

or rooms 22. Within the circle defined by the connecting walls 21 a central inclosure 23 is formed, and access is to be had to this inclosure from a point exteriorly of the building through doors 24. These doors 24 divide the central inclosure forming a runway 25, and the runway leads outwardly to a stationary platform 26.

As illustrated to advantage in Figure 2, the pit 19 is provided with an inclined bottom wall 27 which effects drainage of water and other liquids into what is termed a well 28. This well 28 is of circular form and as illustrated in Figure 1 slopes downward and outward from the platform 26 to a point diametrically opposed with respect to the platform wherein the well communicates with a sump 29. Formed on the inclined wall of the pit 19 is a track bed 30 upon which are secured rails 31 constituting a circular track. Movable on the track is a circular wheeled carriage made up of a plurality of sections and each section comprising a pair of arcuate beams 32 upon which pairs of wheels 33 are mounted for engagement with the rails. The ends of the beams of any one section have rabbeted engagement with the beams of adjacent sections as indicated at 34, and in this manner the several sections are maintained in end to end relation to form the circular carriage.

A sectional crown gear 35 is fixed to the inner beams 32 of the movable carriage to be engaged by a gear 36 fixed to the outer end of a shaft 37, the latter extending through a suitable opening 38 formed in the earth for connection with a conventional form of reduction gearing 39 located in a pit 40. The reduction gear in turn is adapted to be driven by an electric motor 41 whereby the shaft 37 and the gear 38 are constantly driven in one direction thereby effecting continuous rotation of the crown gear and carriage in a clockwise direction as when viewed in Figure 1.

For supporting automobiles on the movable carriage a circular platform is provided, and this platform is constructed of a plurality of arcuate sections, each section comprising curved beams 42 connected by cross ties 43, the latter being arranged in spaced relation to each other so as to allow the free drainage of water through the platform sections and into the pit 19. The opposite ends of the beams 42 have rabbeted engagement

with those of adjacent sections as shown. To maintain the platform sections against displacement from the movable carriage, the platform sections are provided with dowel pins 44 which are removable in sockets or openings 45 formed in the beams 32 of the carriage sections. In this manner the platform sections are held against lateral displacement but the upward displacement thereof can be readily effected to provide access to the pit when desired.

The outer wall 16 of the building is provided with an entrance, and within this entrance between the inner and outer walls 16 and 17 is arranged the stationary platform 26. As shown in Figure 3, this platform is superposed with respect to the movable platform to allow the free rotation of the latter therebeneath. As shown in Figure 1, the stationary platform 26 is inclined at its opposite end in the direction of the movable platform so as to reduce as much as possible the distance between the two and thus minimize the drop or elevation of an automobile passing off of the platform 26 to the movable platform or vice versa.

To guide an automobile from the platform 26 to the rotating platform one end of the former is provided with a raised portion or projection 46 which is tapered as shown to allow the ready movement of the front wheels of a motor vehicle into straddling relation to the projection whereby upon continued movement of the vehicle front end first it will be guided centrally onto the movable platform. The other end of the platform 26 is formed with an arcuate projection 47 designed to guide automobiles discharged onto the platform from the movable platform and in such manner that they will be directed off of the platform with their front ends first and onto an inclosure 48. The inclosure 48 constitutes a subsidiary entrance to the building and may be divided into rooms or compartments as shown.

In the operation of the apparatus, the carriage together with the movable platform is continuously rotated in a clockwise direction as when viewed in Figure 1 so that the movable platform is passing in a direction away from the left hand end of the stationary platform, and in a direction toward the stationary platform at the right hand end of the latter. At intervals around the movable platform are arranged suitable apparatus for manipulation by the operators to effect a thorough cleaning and polishing of an automobile so that during the travel of an automobile from the discharged end of the stationary platform to the receiving end thereof it is successively subjected to the several cleaning and polishing operations. For example, an automobile discharged onto the movable platform from the left hand

end of the stationary platform is first subjected to a cleaning action by playing thereon needle sprays of cold water. In Figure 2, we have shown one form of apparatus which may be used for this purpose, such apparatus including a flexible hose 49 suspended from a support by means of a cord 50 and adapted to be swung by a manual manipulation of a cord 51 from a platform 52. In this manner the spray from the hose 49 can be played over the entire top of the car. As the car advances under the movement of the movable platform, it moves clear of the spraying apparatus when a gang of operators sponge off with warm water the body and fenders of the vehicle. After this operation, during which the vehicle is continuously moving, it is subjected successively to other cleaning operations and finally to the necessary polishing operations so that by the time it reaches the right hand end of the stationary platform it is completely cleaned and polished. As the vehicle advances toward the stationary platform its front wheels ride onto the stationary platform and at opposite sides of the projection 46 whence it is guided off of the stationary platform and into the inclosure 48.

In practice, automobiles are successively deposited on the movable platform and as rapidly discharged from the movable platform back onto the stationary platform and with each car thoroughly cleaned and polished during its course of travel around the apparatus.

The water and other fluid matter embodied in the cleaning of the automobiles is free to drain through the movable platform and carriage into the pit 19, the inclined bottom 27 causing this matter to drain into the well 28 and by virtue of the sloping of the latter as previously described, it will be clear that the fluid matter will drain into the sump 29. In this manner the pit and well will be kept comparatively clean, but when necessary access can be readily had to the well for cleaning purposes by removing one or more of the carriage and platform sections.

In Figures 1 and 4, we have shown a projection 54 movable in a slot 55 of the stationary platform 26 adjacent to the projection 46. This member 54 is normally urged upwardly by springs 56 but is capable of being depressed to accommodate a registering device 57. By this arrangement, it will be seen that a vehicle moving onto the stationary platform will engage the projection 54 and depress the latter to accommodate the device 57, thereby keeping an accurate record of the number of machines delivered to the rotary platform. It is to be understood that the operation of the registering device is such that it requires

two successive depressions of the projection in order to register the passage of a single vehicle.

Although we have herein shown and described only one form of apparatus for cleaning and polishing automobiles embodying our invention, it will be understood that various changes may be made without departing from the spirit of our invention and the spirit and scope of the appended claims.

What we claim is:

1. In an apparatus of the class described, means constituting a combined entrance and exit for an automobile, and a movable platform correlated with said means, whereby to permit an automobile to be driven front end first therefrom onto said platform and driven front end first from the platform back to said means and in such manner that the automobile remains on the platform between the two driving operations.

2. An apparatus of the character described comprising a movable platform supported for rotation, means for continuously rotating the movable platform, a stationary platform superposed with respect to the movable platform, means by which a vehicle is guided on to the movable platform, and means by which a vehicle discharged on to the stationary platform from the movable platform is guided from the stationary platform.

3. A structure of the class described comprising an annular platform, means for continuously revolving the platform, and means to permit automobiles to be driven onto said platform while the latter is in motion and for causing the automobiles to be arranged in an annular series thereon with one directly behind another and with their front ends facing in the same direction.

4. An apparatus of the character described comprising a movable platform, means for continuously rotating the plat-

form, and a stationary platform superposed with respect to the movable platform whereby vehicles can be delivered to the movable platform and discharged therefrom.

5. An apparatus as embodied in claim 4 wherein the stationary platform is provided with projections for guiding vehicles therefrom on to the movable platform, and for guiding vehicles discharged on to the stationary platform.

6. An apparatus of the character described comprising a circular track, a circular wheeled carriage movable on the track, a circular platform supported on and fixed to the carriage, means for continuously rotating the carriage, a stationary platform above the first platform, and means on the stationary platform for guiding vehicles therefrom on to the first platform and for guiding vehicles from the stationary platform discharged thereonto from the first platform.

7. In an apparatus for use in the cleaning and polishing of automobiles, an annular revoluble horizontal platform, and a combined entrance and exit at one point in the circle of the platform, said entrance and exit correlated with the platform so that automobiles may be positioned on the platform in an annular series with one directly behind another and with their front ends forward.

8. An apparatus of the class described comprising an annular platform, means for continuously revolving the platform, and means to permit vehicles to be driven on to the platform while the latter is in motion, for causing the vehicles to be arranged in an annular series thereon, with one directly behind the other, and to cause discharge of the vehicles from the platform in the same order as delivered thereto and while the platform is in motion.

LOUIS J. WILDE.
